DESIGN FOR A BICYCLE

Walter V. Smith, Toledo, Ohio, assignor to The American-National Company, Toledo, Ohio, a corporation of Ohio

Application April 4, 1938, Serial No. 76,286

Term of patent 7 years

To all whom it may concern:

Be it known that I, Walter V. Smith, a citizen of the United States of America, residing at Toledo, in the county of Lucas, in the State of Ohio, have invented a new, original, and ornamental Design for a Bicycle, of which the following is a specification, reference being had therein to the accompanying drawing, forming a part thereof, wherein:

The figure is a side perspective view of a bicycle embodying my new design.

The dominant features of the invention reside in the frame portion illustrated in full lines.

I claim:

The ornamental design for a bicycle, substantially as shown and described.

WALTER V. SMITH.
